TORPEDO DEFLECTING SHIELD

Ernest Hegewald, Jersey City, N. J.

Application December 31, 1942, Serial No. 470,755

1 Claim. (Cl. 114—240)

This invention relates to new and useful improvements in torpedo deflecting shields for ships, and has for its principal object the provision of a novel shield which will form an effective protection for the full length of the ship, including the fore and aft sections, and will provide such protection by novel means which cause the torpedo to be deflected completely under the ship, and without causing such torpedo to explode.

Foraminous screens mounted in spaced relation to a ship have been frequently suggested as a means for causing the torpedo to harmlessly explode a safe distance from the ship. Just what is a safe distance has never been definitely determined, since all devices of this general character have fallen far short of the expectations of their creators. These devices have, for the most part, been open to three general objections. First, they are so cumbersome as to greatly reduce the speed of the ship, thus actually making the ship a better target for the torpedo than it would be if its normal speed were preserved. Second, the shields or nets which have actually been tried have been improperly braced, and in the first substantial sea the whole apparatus has been ripped off the ship. Third, the torpedo normally travels at such speed as to rip through the shield and hit the side of the ship.

The device of the present invention is a new departure in the art, and completely eliminates the foregoing difficulties. In the first place, the instant shield does not aim to stop the torpedo, nor to explode it some distance from the ship, but rather to deflect it in such a manner as to cause it to pass completely under the ship, without, however, exploding the same. This shield is formed from a plurality of spaced bars which are downwardly and forwardly inclined, thus providing what amounts to a plurality of adjacent channels which lie at an angle of 45°, more or less, to the side of the ship. The torpedo strikes one of these channels and is deflected downwardly, as can be well understood. The channels formed, however, are not complete channels, since they comprise merely two bars of sufficient spacing to engage the nose of the torpedo without coming in contact with the detonating element which is normally located at the central portion of such nose.

The shield is preferably made in a plurality of jointed sections of generally similar construction extending over the major portion of the length of the ship, special sections being provided for the fore and aft sections. The bars are firmly secured at their opposite terminals, and

bracing means are further provided intermediate the ends, which bracing elements, however, do not provide an obstruction which would engage the detonating means at the forward end of the torpedo. In other words, these braces or struts are so arranged as to present no obstacle to the torpedo sliding down the channel. The shield sections lying as they are at an angle of 45°, or thereabouts, to the side of the ship, thus present 10 a large number of these channels, and when the torpedo strikes between a pair of such bars, it is gently eased downwardly, and its forward movement is thus deflected sufficiently to cause it to dive downwardly. It can be well appreciated that a torpedo which is deflected in this fashion cannot quickly recover its equilibrium. When the depth-governing mechanism has had time to 15 again return the torpedo to its predetermined depth of travel, say six or eight feet below the water line, the ship has passed beyond the range 20 of the torpedo.

The torpedo shield of the present invention is further formed in such a fashion as to reduce to a minimum the resistance to the forward movement 25 of the ship, and any reduction in the effective speed of the ship is particularly small when compared to the great safety factor provided by the shield of the present invention. The second objection to the devices earlier proposed is also 30 eliminated by the present shield. In all of such previous devices, suitable arms extended outwardly from the ship, both at the top and the bottom of the shield. In the shield of the present invention, however, the lower ends of the shield sections are firmly secured to brackets carried by the ship itself, and thus the lower end of the shield which must bear the greatest resistance is firmly secured to it without any transversely disposed arm. The lower end of the shield thus 35 being rigidly secured, the upper end has far less resistance, and novel means are provided for firmly securing such upper ends in proper spaced 40 relation to the ship.

Another object of the present invention is 45 the provision of a shield of this character which may be quickly and easily drawn to the side of the ship when such ship is in port, thus eliminating the obstruction which is most important in loading and unloading the ship. A further object of 50 the present invention is the provision of novel fore and aft shield sections, which likewise can be readily drawn adjacent to the side of the ship with a minimum amount of effort.

The drawings are generally schematic in character, and are not intended as working drawings,

but rather are designed primarily to show the basic principles underlying the present invention. In such drawings:

Fig. 1 represents a plan view of the shield in operative position on one side of a ship.

Fig. 2 is a side elevation thereof.

Fig. 3 is an enlarged, detailed side elevation of the rear sections of the shield drawn upwardly into inoperative position adjacent to the side of the ship.

Fig. 4 illustrates the forward sections of the shield drawn into inoperative position.

Fig. 5 is a broken plan view showing the overlapping portions of the forward part of the main side section of the shield, and the rear portion of the fore section in overlapping relationship when drawn into inoperative position.

Fig. 6 is a broken sectional view of the main side sections of the shield.

Fig. 7 shows the same shield drawn into inoperative position adjacent to the side of the ship.

Fig. 8 is a broken plan view of the upper bracing element connected at its inner end with the ship, and at its outer end with the upper edge of the shield.

Fig. 9 is a broken transverse section taken on line 9-9 of Fig. 8.

Fig. 10 is a broken transverse section taken on line 10-10 of Fig. 8.

Fig. 11 is an end elevation of the aft section of the shield, the view showing on the right-hand side the position of the several aft sections in operative position, and on the left side showing the position of such sections in inoperative position.

Fig. 12 similarly shows the forward shield sections.

Fig. 13 is a broken longitudinal section taken on line 13-13 of Fig. 8.

Fig. 14 is similar to Fig. 6, but shows a modification in the shield construction.

Fig. 15 is a broken section taken on line 15-15 of Fig. 14.

Referring now to Figs. 1 and 2, it will be noted that the ship, which is designated by the reference numeral 10, is provided with a shield forming a main side section 11, three forward sections 12, 13 and 14, respectively, and rear sections 15 and 16, respectively. The main side section 11 may be formed as a single rigid section, or in a plurality of sub-sections, depending somewhat upon the length of the ship and upon other factors. Such section comprises a plurality of spaced bars 20 which are inwardly turned at their upper ends to form a loop 21 which is secured by welding, or otherwise, at 22. A somewhat similar loop 24 is formed at the lower end of each bar, and is secured at 25 to the main section of the bar. A brace or strut 26 is further carried by the bar, such brace being secured by welding, or otherwise, to a longitudinal shaft 28, which, in turn, is journalled in spaced brackets 29 secured adjacent the lower edge of the side of the ship 10. The loop 21 at the upper end of each bar is secured at 32 to another longitudinal shaft 33.

In addition to the support afforded by upper and lower shafts 33 and 28, respectively, the spaced bars are maintained in such relation intermediate their ends by means of struts or braces 36 and 37, which are secured at their terminals on the bars 20 and extend inwardly from the outer surface of the shield. At their apices they are suitably secured to longitudinal bars 39 and 40. It will accordingly be seen that whether

the main side section is formed in one or more individual sections, or in a single section, it is made up of the spaced bars, each adjacent pair of which forms a channel which acts as a slide-way for the torpedo. The several spaced bars 20 are not vertical, but rather are disposed at an angle to the vertical. The main side section is thus firmly secured pivotally at its lower end by means of brackets 29, and at its upper end the section is secured in its spaced relation to the ship by means of a novel arm structure 42 shown in detail in Figs. 8, 9, 10 and 13.

Each bracket arm 42 includes a generally U-shaped structure 43 formed with a cross-piece 44 at its outer terminal, an intermediate transverse piece 45, and ring elements 46 at its inner terminals. These ring elements are carried on a shaft 47 which is journalled in brackets 48 rigidly secured to the side of the ship at a point which may be just above or even below the normal water line of the ship. When in operative position, the bracket arm 42 is in generally horizontal position, as shown in Fig. 6, and rigidly secures the side section 11 at its outer terminal inoperative position. When the side section is drawn to inoperative position, as shown in Fig. 7, a slideable element or block 50, having an aperture 51 which receives upper longitudinal shaft 33, moves along the bracket arm by virtue of the following arrangement. Spaced angle elements 52 and 53 provide slideways for block 50, as shown in Figs. 8 and 9, and the vertical portions of such angle irons are cut away at the opposite terminals thereof. These terminal sections are bent to form a ring 54 at their inner terminals which are received upon transverse bar 45. At their outer terminals, rings 57 are formed which are received on outer transverse portion 44.

Block 50 is normally maintained in its outermost position, shown particularly in Fig. 8, by means of a pair of curved pawls 58 which are pivotally mounted at 59 on a slideable block 60. Block 60 is formed with opposed flanges 61 which are received in slots 62 of the vertical portions of angle members 52 and 53. A spring 64 urges pawls 58 towards each other. Angle members 52 and 53 form a support for pins 66. It will accordingly be seen that when it is desired to release block 50, block 60 is moved in the direction of the ship, which movement causes pawls 58 to engage pins 66, thus moving the pawls outwardly to a point where they are out of engagement with block 50, thus permitting block 50 to move inwardly along the tracks afforded by angle members 52 and 53. Block 60 may be manipulated by means of a shaft 70 which is journalled for longitudinal movement in a plate 71 welded, or otherwise secured, between angle members 52 and 53. At its inner end the shaft is provided with a ring 72 which receives a line 73 which may be manually drawn from the deck of the ship. Block 60 may be normally retained in the position shown in Fig. 8 by means of a spring 69; although a more positive locking element, such, for instance, as a removable pin passing through the block and the supporting flanges, may be employed.

Accordingly, it will be seen that when the shield 11 is to be drawn from operative position, as shown in Fig. 6, to inoperative position along the side of the ship, as shown in Fig. 7, line 73 is first drawn inwardly, thus releasing pawls 58, and the shield is then moved to its vertical position by means of a cable 74 connected at 75 to the bracket arm, which cable is drawn by some

suitable source of power on the ship. It will be noted in Fig. 2 that a portion of the bars 20 in intermediate section 11 is inclined in one direction, and another portion inclined in the opposite direction. These bars may, of course, be substantially vertical, although it is preferred to have them inclined downwardly and forwardly, as shown in the left-hand portion of section 11 in Fig. 2. Further experiment may prove that the opposite inclination gives the best results.

Referring now to the forward sections 12, 13 and 14, it will be noted in Fig. 4 that section 12 is also formed from bars 20 the same as section 11, such bars being connected at their ends by means of the lower and upper shafts 28 and 33, respectively, and by the intermediate, longitudinal, bracing bars 39 and 40. The entire section 12 is otherwise formed generally similar to section 11 in that it is provided with the struts or braces 26, 36, 37 and 21, shown more clearly in Fig. 6 in respect of section 11. Section 12 preferably moves independently of section 11, since when these two sections are drawn to inoperative position alongside the ship, they overlap somewhat at their upper meeting terminals, as shown in Figs. 4 and 5. Section 13 is generally triangular in shape, although otherwise it may be formed in the same general manner as sections 11 and 12. It is hinged along one side to the forward terminal of section 12 by means of hinge element 75. Section 14 is also generally triangular in shape and is hinged at 76 to a second edge of section 13. It will thus be seen that when the several shield sections are in operative position lying at an outwardly-inclined angle from the side of the ship, each adjacent pair of generally vertical bars forms a slideway which deflects the torpedo, causing it to alter its path and travel under the ship.

When the shield is in inoperative position, sections 13 and 14 may occupy the position shown in Fig. 4 in order to permit the anchor to be dropped. When, however, the shield is to be moved into operative position, section 12 is released, and when it has come to its outermost position, as shown in Fig. 12, sections 13 and 14 are then moved forward and generally occupy the position shown in Fig. 2. Sections 13 and 14 are further supported by means of a load-carrying cable 80 secured at one end to section 13, as shown in Fig. 2, and at the opposite end to the ship. A second cable 81 is secured to the outermost point of section 13 and is brought around the opposite side of the ship where it is suitably secured on the deck. A third cable 82 is secured at its lower end to the lower outermost point of section 14, and at its opposite end to a suitable

position on the deck on the opposite side of the vessel.

Rear section 15, shown particularly in Fig. 3, is likewise formed with inclined bars 20 and the upper and lower shafts 33 and 28, respectively, and with the intermediate bracing bars 39 and 40. Section 16 is hinged at 85 to the rear edge of section 15 and is formed substantially similar to sections 13 and 14, except for the shape. It is further provided with an offset portion 17 at its rear terminal which provides protection for the rudder and propeller. Additional support is provided for rear sections 16 by means of a cable 87 which is connected with a spar 88 extending rearwardly from the stern in the center of the vessel. At the lower outer terminals of portion 17, a second cable 89 from the left-hand section may be secured to bitt 90, and another cable 91 may be secured to bitt 92.

The modified form of shield 94, shown particularly in Figs. 14 and 15, includes a plurality of spaced bars 95 which are formed generally similar to bars 20 in the several shields previously described. In this instance, however, the shield is further formed with a plurality of inwardly disposed, spaced bars 96 which may be inclined at a different angle than bars 95. Suitable struts or braces 97 connect the outer bars 95 with the inner bars 96, and in this instance, again, the struts or braces 97 are so disposed as to present no obstacle to the passage of the torpedo down the channels formed by the outer bars 95.

The several embodiments of the invention herein disclosed are generally illustrative of the invention, but are not to be taken in any limiting sense.

What I claim is:

A torpedo shield of the character described for ships and the like, such shield comprising a plurality of interconnected sections lying at an angle of 45°, or thereabouts, to the side of the ship, and connected at their lower ends to the side of the ship adjacent the turn of the bilge thereof, bracket arms connecting the upper ends of the sections with the ship, each section comprising a plurality of generally parallel, spaced bars inclined forwardly at their lower ends, means for retaining the bars in such spaced relation comprising a plurality of longitudinal supporting elements lying inside the plane of said spaced bars, and bracket means connecting the bars with the supporting elements, the spacing between the bars being less than the diameter of the usual torpedo, each pair of adjoining bars forming a slideway to deflect the torpedo below the ship.

ERNEST HEGEWALD.
